UNITED STATES PATENT OFFICE.

VICTOR V. LAWRENCE, OF WATERFORD, VERMONT, ASSIGNOR OF ONE-HALF TO ISAAC F. PAUL, OF BOSTON, MASSACHUSETTS, AND AMOS H. CARPENTER, OF WEST WATERFORD, VERMONT.

ROTARY PLANING-MACHINE.

SPECIFICATION forming part of Letters Patent No. 406,587, dated July 9, 1889.

Application filed August 29, 1888. Serial No. 284,104. (No model.)

To all whom it may concern:

Be it known that I, VICTOR V. LAWRENCE, a citizen of the United States, residing at Waterford, in the county of Caledonia and State 5 of Vermont, have invented certain new and useful Improvements in Rotary Planing-Machines; and I do hereby declare that the following is a full, clear, and exact description of the same.

10 My invention relates to an improved presser-bar attachment for a rotary cutter-head, as hereinafter pointed out.

In the accompanying drawings, Figure 1 is a sectional elevation of my improved presser-bar 15 arranged in working position with an ordinary cutter-head. Fig. 2 is an end elevation of the presser-bar, together with a hollow cutter-head, of my invention. Fig. 3 is a vertical cross-section of the parts shown in Fig. 2.

20 Fig. 4 is a detail view showing the inner side of the presser-bar. Fig. 5 is a vertical cross-section of a modification of my presser-bar, together with a modification of the cutter-head shown in Figs. 2 and 3.

25 The presser or presser-bar A has substantially the form of a segment of a hollow cylinder of greater diameter and length than the rotary cutter-head B. It is arranged with its concave side close to the front side of said 30 cutter-head, so that at each rotation a portion of the latter projects into and sweeps through the cavity of the presser-bar, as shown by dotted lines in Figs. 1 and 3. The lower side 1 of the presser-bar A is beveled or inclined to form a bed or seat on which a rigid

35 cutter 2 rests. The latter is a flat plate, made preferably coequal in length with the presser-bar head 1. The beveled portion of its edge bears on the top of the board C in close proximity to the point or line where the cutting-edges of the knives 3 of the cutter-head B leave the surface of said board. The edge of the cutter 2 coacts with the cutting-edges of the knives 3 of the cutter-head B to sever the 40 chips or shavings as they are raised from the board by said knives, thus preventing the latter, to a large extent, from stripping or tearing the chips or shavings from the board, so that its planed surface is left smoother than 45 would otherwise be the case. The cutter 2 is

adjustably secured to the bed 1 of the presser-head by clamp-screws 4, which pass through transverse slots, and is also provided with set-screws 5, which are fitted to work in brackets 6 on said head 1, their points bearing against the back of the cutter 2, so that by loosening the clamp-screws 4 and rotating the said set-screws 5 the cutter may be adjusted as required for taking a thin or thick shaving.

In addition to the ordinary free action of 60 the presser-bar, it also serves as a guard to catch chips and shavings and turn them back to a point where they may be conveniently withdrawn from the bed of the machine by a blower or exhaust-fan in the usual manner. 65 The presser-bar A is hinged on the journals 7 of the cutter-head B to enable its cutter 2 to rise and fall and thus pass over knots or inequalities in the board C. The means for thus hinging the presser-bar are horizontal 70 arms 8, having their outer or free ends provided with lengthwise slots and their inner ends curved corresponding to the journal-boxes of the cutter-head B, to which they are secured by detachable semicircular pieces 9. 75 The arms 7 are thus free to rotate on the cutter-head journals as centers. The presser-bar is attached to these arms by clamp-screws 10, which pass through the slots in the arms. By this construction and combination of parts 80 the presser-bar may be adjusted toward or from the cutter-head as required.

I sometimes curve the plate 2 downward to enable it to pass under the cutter-head more readily, and bevel it on its upper instead of its lower side at its cutting-edge, as shown in Fig. 5. In such case holes 11 are provided in the presser-bar to allow insertion of a screw-driver for adjusting the set-screws 5. The outer ends of the arms 8 may also be 90 arranged inside the ends of the presser-bar, as shown in said Fig. 5.

The hollow or slotted cutter-head shown in the drawings forms the subject of an application for patent filed by me March 26, 1888, 95 Serial No. 268,488.

What I claim is—

1. The combination, with the rotary cutter-head, of arms 8, which are journaled on the same axis and provided with slots, the presser- 100

bar having an inclined cutter-seat 1 on its lower side, clamp-screws 10, which secure the cutter to said arms in any adjustment permitted by the slots, and the cutter 2, attached to the inclined seat 1, and screws for securing and adjusting said cutter, as shown and described.

2. The combination, with the rotary cutter-head, of horizontal arms which are journaled on the same axis and provided with slots, the presser-bar, and clamp-screws which secure the latter to said arms in any adjustment per-

mitted by the said slots, as specified and described.

3. The combination, with the rotary cutter-head, of a presser-bar which is journaled on the same axis and is adjustable toward and from the cutter-head, as specified and described. 15

VICTOR V. LAWRENCE.
